UNITED STATES PATENT OFFICE

HARVEY D. WILLIAMS, OF WALLINGFORD, CONNECTICUT, ASSIGNOR, BY MESNE ASSIGNMENTS, TO SECURITY TRUST COMPANY, OF DETROIT, MICHIGAN, A CORPORATION OF MICHIGAN

TOOTHED GEARING

Original application filed July 25, 1914, Serial No. 853,017, and in Great Britain May 6, 1914. Divided and this application filed September 20, 1919. Serial No. 325,216.

My present invention, for which I have filed applications in Great Britain May 6, 1914, and in France October 6, 1914, relates to gear wheels, and has particular reference to that type of gearing in which two successive working tooth-surfaces (whether on the same tooth or at the same tooth-space) constitute a pair related in a particular manner to a "master-form axis" located between the two tooth-surfaces of said pair. My invention is designed for use in cases in which one of the meshing gears (hereinafter referred to as the "wheel") has its working tooth-surfaces formed according to a single-reproduction configuration, while the other gear (hereinafter referred to as the "pinion") has its working tooth-surfaces formed according to a compound-reproduction configuration and conjugate to those of the said "wheel". The present application is a division of my application for Letters Patent filed in the United States Patent Office on July 25, 1914, Serial No. 853,017, and renewed on December 5, 1917, Serial No. 205,664, on which Letters Patent No. 1,324,287 were issued on December 9th, 1919.

Most of the figures of the drawings of my said Letters Patent disclose a form of my invention in which the "master-form axis" lying between the two tooth-surfaces of the same pair, on the "wheel", is a straight line, so that both surfaces of such pair may be produced in a very simple manner, by the rectilinear reciprocation of a tool the profile of which corresponds to that of a tooth or of a tooth-space. According to the species of my invention forming the subject-matter of the present application, the two surfaces of the same pair, on the wheel having tooth-surfaces of single-reproduction configuration, are such as may be produced by the motion of a suitable tool along a curvilinear path, and more particularly, along a circular arc, that is to say, the master-form axis is no longer straight, but curved, preferably according to the arc of a circle. The present species of my invention was also described and illustrated in my earlier application above referred to, at the time of its filing. Reference is to be had to the accompany-

ing drawings, in which Fig. 1 is a partial end view of a spur wheel and a mating pinion embodying this invention; Fig. 2 is a face view showing a portion of the peripheral surface or tooth-zone of the wheel shown in Fig. 1; Fig. 3 is a partial face view of the tooth-zone of a bevel wheel formed according to this invention; Fig. 4 is a similar partial view of a skew bevel wheel embodying this invention; Fig. 5 is a cross section on line 5—5 of Figs. 2, 3, and 4; Fig. 6 is a cross section of another form of the wheel, taken on the same plane as Fig. 5; Fig. 7 is a perspective view of a portion of a bevel pinion constructed according to this invention; and Fig. 8 is a diagram illustrating certain relations set forth hereinafter; and Fig. 9 is an end view of the tools employed for cutting the working tooth-surfaces on the wheel and on the pinion.

In Figs. 1 and 2, I have shown a spur wheel B having a tooth-zone N' across which extend the skew working tooth-surfaces arranged in pairs, the two surfaces of the same pair, as f^3 , f^5 , being formed of longitudinal circular-arc elements all parallel to a circular-arc master-form axis α^{13} which lies between said tooth-surfaces and intersects obliquely the two planes at the ends of said tooth-zone. In the particular case here shown, the surfaces f^3 , f^5 are at the same tooth-space F, and h indicates a portion of the tooth lying in the tooth-zone between two adjacent tooth-spaces. The axis of the wheel is indicated at α^3 , and the parallel axis of the mating spur pinion P at d , while α designates the instant axis which is parallel to the axes α^3 and d and which intersects the master-form axis α^{13} at a point half-way between the end surfaces of the tooth-zone, which point lies on the median pitch-circle 7 of the wheel B and on the median pitch-circle 8 of the pinion P, the latter having teeth g the working surfaces of which are conjugate to those of the wheel, as will be set forth more fully hereinafter. At e^6 , Fig. 2, I have indicated the angle of obliquity which the master-form axis (that is, a tooth-zone secant thereto) forms with the instant axis α . Inasmuch as the surfaces f^3 , f^5 consist of curvi-

linear longitudinal elements all parallel to the same master-form axis x^{13} , the latter being a circular arc, it will be obvious that both surfaces of the same pair may be produced at the same time by moving (rotating) in a corresponding circular path, a tool, such as J (Fig. 9) having the same cross sectional shape as the tooth-space, the shape of the latter being shown best in Fig. 5. The wheel or 10 wheel-blank would remain stationary during this production of a pair of tooth-surfaces, so that they may be said to be formed according to a single-reproduction configuration. It will be obvious that when the wheel 15 and pinion are rotating in a certain direction, say the one indicated by the arrow n^7 in Fig. 1, only one surface of each pair of surfaces of the wheel and of the pinion will be in driving co-operation, the other surfaces of such pairs 20 acting simply to prevent backlash. Inasmuch as generally it is desirable to have the gears transmit power equally well in either direction, I prefer to have the two tooth-surfaces of the same pair disposed symmetrically 25 to the central line m^2 which intersects the master-form axis (see Figs. 5 and 8).

In Fig. 3 I have illustrated a bevel wheel with tooth-surfaces arranged in pairs, the 30 two tooth-surfaces of the same pair having the same relation to each other and to their master-form axis as in Figs. 1 and 2. The secants subtending the tooth-zone arcs of the master-form axes x' of the several pairs of tooth-surfaces f^3, f^5 , will, if extended, pass 35 through the apex c' of the wheel-cone, of which the tooth-zone N forms part; the secants subtending the longitudinal arcs at the bottom edges of the working tooth-surfaces are substantially tangential to a circle t^3 , and 40 the secants subtending the longitudinal arcs at the upper edges of said tooth-surfaces are substantially tangential to a circle t' , each of said circles having its center on the axis of the wheel-cone. The spacing of adjacent 45 master-form axes x' is uniform, as indicated by the angle or arc l' , but owing to the formation on the tooth-surfaces of the same pair, of parallel longitudinal line-elements, each action-face or driving face of the wheel, say 50 f^5 , has a rearward skew, the extent of which is indicated by the angle or arc e^{13} . The wheel teeth h intervening between the adjacent tooth-spaces F are tapered inwardly. The tooth-spaces themselves are of uniform width 55 or cross section from end to end, if such cross section be taken in planes perpendicular to the respective master-form axis x' . It will be seen that a pair of surfaces, such as 21 and 60 22, formed of parallel longitudinal elements, is followed by another pair of surfaces, as 23 and 24, also composed of parallel longitudinal elements, but the longitudinal line-elements of the surfaces 21, 22 are not parallel to the similar elements of the surfaces 23, 24, 65 but in a convergent relation thereto, as indi-

cated by the angle l^2 . Thus, of any three successive tooth-surfaces, two have the same master-form axis and are composed of longitudinal circular-arc elements parallel to said axis, while the third surface has longitudinal line elements parallel to another master-form axis. This relation as regards the working tooth-surfaces of the "wheel" is true of all forms of my invention shown herein.

In Fig. 4 I have illustrated what may be termed a skew bevel wheel having working tooth-surfaces arranged in pairs on the tooth-zone N' of the wheel body B, in substantially the same manner as described with reference to Fig. 3. The difference lies in the direction of the tooth-zone secants subtending the master-form axes, indicated at x^{12} , which secants, instead of passing through the axis of the cone (as does the instant axis x), have a strong obliquity or skew, as indicated by the angle e^6 . The axes x^{12} are circular arcs as before.

The rearward skew indicated at e^{13} in Fig. 3, and the similar but greater skew obtained with the arrangement shown in Fig. 4, result in a very gradual meshing of such wheels with their respective pinions, thus securing a very smooth operation.

As stated above, any one of the three kinds of wheels shown, may have its tooth-surfaces formed in pairs, by moving (rotating) in a path corresponding to the position of the corresponding master-form axes x^{13}, x' , or x^{12} respectively, a tool, such as J in Fig. 9, having a profile corresponding to that of the tooth-space F (Fig. 5), the wheel body or blank being held stationary during the motion of the tool. Of course, a relative circumferential movement of the blank and tool (the so-called "indexing") is effected after one pair of tooth-surfaces has been completed, to bring the tool into working relation to another pair of tooth-surfaces.

The pinion P (Figs. 1 and 7) is formed with teeth g the working tooth-surfaces of which, j^2 , terminate at the tooth-zone in edges j^3 . These tooth-surfaces may be formed in pairs by means of a tool, such as T, which is a counterpart of the tool J employed for forming a pair of tooth-surfaces on the wheel. While in the case of the wheel, the profile of the tool J is shown as corresponding to that of a tooth-space F, so that said tool may produce at the same time two tooth-surfaces located at the same tooth-space, the corresponding pinion-cutting tool T has a profile corresponding to that of the cross section of a pinion-tooth g , so that said tool may produce at the same time two tooth-surfaces on the same tooth. The operation might be reversed, that is, the tool T might be employed to cut a pair of tooth-surfaces f^3, f^5 on the same tooth of the wheel B, as indicated in Fig. 6, in which case the counterpart tool J would be employed for producing on the

pinion P, pairs of tooth-surfaces, each pair being at the same tooth-space. Whether the tool J or the tool T is employed in conjunction with the wheel B, the motion of such tool would be in a curvilinear path, and preferably in the arc of a circle, as referred to above. In cutting the pinion tooth-surfaces, the pinion blank and the tool would be given a relative movement such as the tooth-surfaces of the wheel have relatively to those of the pinion when these two gears are operating in mesh with one another, the pinion-cutting tool corresponding to the tooth-surfaces of the wheel, or rather to a pair of consecutive tooth-surfaces of the wheel. In addition to this relative rolling movement of the tool and pinion blank, the tool would be given a longitudinal cutting movement in a curved path, and specifically in a circular arc, so that at one cutting movement or cutting stroke of the tool, two points of said tool will cut longitudinal parallel lines such as i, i' on the two tooth-surfaces of the same pair, said lines being arcs of circles corresponding to the path of the tool. Of course, owing to the relative rolling motion just referred to, the pair of parallel lines cut at the next stroke of the tool will not be parallel (on the surfaces j^2) to the pair i, i' first mentioned; still, the two surfaces j^2 of the same pair will be composed of longitudinal line elements in the nature of circular arcs, each line element of one surface having a corresponding line element, parallel to it, on the other surface of the pair. From the mode of production described it follows that while the two tooth-surfaces of the same pair on the wheel will have an untwisted form or construction, owing to their single-reproduction configuration, the mating pair of conjugate pinion tooth-surfaces, owing to their peculiar compound-reproduction configuration, will have a twist throughout their length.

In the diagram Fig. 8, x^3 indicates the axis of the wheel-blank B, m^3 and m^4 are circles of equal radii, having their centers on said axis at c and c' respectively, and each lying in a plane of rotation, that is to say, these two circles lie in parallel planes perpendicular to the axis x^3 ; the circle m^3 may be said to be described by the end of the radius m^2 rotating about said axis, and this circle indicates the geometric pitch-surface corresponding to the pitch-circle 7 indicated in Figs. 1 and 2. The outer end of the radius m^2 is designated as xx , and lies in the instant axis. At c', y I have indicated a radius parallel to m^2 , the point y lying on the circle m^4 . With the point y as a center, and y, c' as a radius, I have drawn a circle m^5 , having a radius 3^b perpendicular to y, c' . This circle may be described as the orbital path of the point z (at the outer end of the radius 3^b) around the point y .

The vertex xx and the points y, z lie in a plane

right-angled triangle the plane of which is tangential to the geometric pitch surface, said surface being the geometric surface of revolution generated by the line m' (connecting xx with y) revolving about the wheel-axis x^3 . This triangle xx, y, z has its hypotenuse x^{13} ($xx-z$) curved according to the arc of a circle and forming the master-form axis of the pair of tooth-surfaces cut on the wheel by a motion of the tool in a path corresponding to said master-form axis; in this case, the tooth-zone of the wheel (as N'' in Fig. 2) being located contiguous to the meridian circle m^3 of Fig. 8, the gear-wheel will be of the particular kind which I designate as a "skew-spur". In Fig. 8 the position x^{12} of the master-form axis (Figs. 4) is indicated by a dotted curved line, representing another position of the hypotenuse line, and when this location of the master-form axis is employed, a "skew-bevel" wheel having teeth of the character shown in Fig. 4 will result. Thus the master-form axis coincides in each case with a plane-triangle hypotenuse line, which (in some part of its length) touches the instant axis (as at xx) and is also located in a geometric plane that intersects a wheel-axis plane (this being the plane of the parallel lines m' and x^3 , Fig. 8) at some point in the instant-axis of the gears, or in the pitch-surface of the wheel. In Fig. 8, the position of the right-angled triangle shown in full lines indicates the side m and the hypotenuse x^{13} of a curved form, and connected by the base line 3^b . While the arrangement here pointed out, as regards the location of the master-form axis in certain planes, applies both to the curvilinear forms of the tooth-surfaces having longitudinally-parallel elements, and to the rectilinear forms disclosed more fully in my pending application above referred to, my present application is specific to those forms in which the master-form axis is curvilinear.

It will be understood that as the tool J or T performs its cutting action, it is also given the usual feeding movement toward the blank so that it may cut into the blank more deeply at successive working movements or cutting strokes.

I claim as my invention:

1. A gear wheel having teeth with working surfaces of single-reproduction configuration, said surfaces being arranged in pairs of adjacent surfaces, the two surfaces of the same pair having curved-line elements parallel to a curved master-form axis located between the surfaces of such pair.

2. A gear wheel having teeth with working-surfaces of single-reproduction configurations, said surfaces being arranged in pairs of adjacent surfaces, the two surfaces of the same pair having line-elements of circular curvature parallel to a master-form axis of

- 5 circular curvature located between the surfaces of such pair.
- 6 3. A pinion having teeth with working-surfaces of compound-reproduction configuration conjugate to tooth-surfaces of single-reproduction configuration containing parallel curved-line elements extending lengthwise of the last-named tooth-surfaces.
- 10 4. A pinion having teeth with working-surfaces of compound-reproduction configuration conjugate to tooth surfaces of single-reproduction configuration containing parallel longitudinal line elements of circular curvature.
- 15 5. A pair of toothed gears adapted to mesh, one of said gears having teeth with working-surfaces of single-reproduction configuration containing parallel longitudinal curved-line elements, and the mating gear having 20 teeth with working-surfaces of compound-reproduction configuration conjugate to the said tooth-surfaces of single-reproduction configuration.
- 25 6. A pair of toothed gears adapted to mesh, one of said gears having teeth with working-surfaces of single-reproduction configuration containing parallel longitudinal line elements of circular curvature, and the mating gear having teeth with working-surfaces of compound-reproduction configuration conjugate to said tooth-surfaces of single-reproduction configuration.
- 30 7. The herein described improvement in toothed gearing, it consisting in a pair of gears comprising a master-wheel provided with teeth each having a working-surface with uniform profiles throughout the length thereof and each surface having surface elements parallel with a geometric master-form axis which coincides with the curvilinear hypotenuse of a curved sided plane-triangle another side of which, at a plurality of points in the length thereof, coincides with a line lying in a geometric plane passing through 40 the wheel axis, the vertex of said triangle being in the instant axis of said gears, and said wheel tooth working surfaces conforming to the single-reproduction configuration, in combination with a mating pinion having a wheel-engaging teeth each provided with a working surface conjugate to said wheel-tooth working surfaces and conforming to the compound-reproduction configuration.
- 45 8. A bevel gear wheel having curved teeth with working surfaces of single reproduction configuration, said surfaces being arranged in pairs of adjacent surfaces, the two surfaces of the same pair having curved line 50 longitudinal elements parallel to a curved master-form axis located between such surfaces.
- 55 9. A bevel pinion having curved teeth with working-surfaces of compound-reproduction configuration conjugate to tooth-surfaces of single-reproduction configuration containing parallel curved-line longitudinal elements.
- 60 10. A bevel pinion having curved teeth with working-surfaces of compound-reproduction configuration conjugate to tooth-surfaces of single-reproduction configuration containing parallel longitudinal elements of circular curvature.
- 65 11. A pair of bevel gears adapted to mesh, one of said gears having curved teeth with working-surfaces of single-reproduction configuration containing parallel longitudinal curved-line elements, and the mating gear having curved teeth with working-surfaces of compound-reproduction configuration conjugate to the tooth-surfaces of single-reproduction configuration.
- 70 12. A bevel pinion having teeth with working-surfaces of compound-reproduction configuration, said surfaces being arranged in pairs of adjacent surfaces, the two surfaces of the same pair being conjugate to tooth surfaces containing parallel curved-line longitudinal elements.
- 75 13. A gear having teeth fashioned with faces conforming to arcuate surfaces of different radius respectively, said surfaces generated from a common center.
- 80 14. A geared couple consisting of a gear having curved transverse grooves in its tooth-bearing part spaced equally about the axis of the gear, the opposite faces of each individual groove being curved about the same center, and the centers of curvature of the several grooves being all different and a complementary gear having a series of teeth similarly spaced, the opposite faces of each tooth having the same curvature as the complementary faces of the grooves in the first gear.
- 85 15. A gear constituting one member of a geared couple having curved teeth and intermediate tooth spaces, the opposite faces of any one tooth being curved about the same generating center with different radii of curvature, and the faces of different teeth being curved about different generating centers.
- 90 16. A gear having teeth with working surfaces of compound reproduction configuration, said surfaces being arranged in pairs corresponding to arcuate surfaces of different radius respectively, said surfaces generated from a common center.
- 95 17. A gear having teeth fashioned with working surfaces of compound reproduction configuration, said surfaces conforming to arcuate surfaces of different radius respectively.
